UNITED STATES PATENT OFFICE.

WILLIAM T. BROOKS, OF WILMINGTON, DELAWARE.

GAME APPARATUS.

1,274,135.

Specification of Letters Patent. Patented July 30, 1918.

Application filed October 12, 1917. Serial No. 196,250.

To all whom it may concern:

Be it known that I, WILLIAM T. BROOKS, a citizen of the United States, residing at 310 E. 24th street, Wilmington, in the county of 5 New Castle and State of Delaware, have invented new and useful Improvements in Game Apparatus, of which the following is a specification.

The invention relates to games and toys 10 and has for an object to provide a game apparatus for amusing grown persons as well as children, and which will prove amusing, interesting and educational.

The invention comprehends among other 15 features, a game apparatus which may be indicative of historical events, various kinds of trades or the names of fruits, vegetables or the like, or taken in connection with countries, States or cities, and may also be 20 employed in the nature of a mimic warfare game, setting forth the operations of a torpedo or a submarine, and for purposes of illustration the game is shown in this manner in the drawings forming a part of this 25 specification.

In the further disclosure of the invention, reference is to be had to the accompanying drawings, constituting a part of this specification, in which similar characters of reference denote corresponding parts in all the 30 views, and in which—

Figure 1 is a plan view of the game apparatus showing the same in open or playing position.

35 Fig. 2 is a vertical transverse sectional view taken on the line 2—2 in Fig. 1.

Fig. 3 is a somewhat similar section showing the game apparatus closed up and the carriage or torpedo body removed.

40 Fig. 4 is a fragmentary vertical longitudinal section showing a portion of the mechanism.

Fig. 5 is a perspective view of the game apparatus in its closed position, and

45 Fig. 6 is a side elevation of the carriage or torpedo body.

Referring more particularly to the views, I employ a casing 10, of a boxlike nature and which is preferably formed in two parts 10^a and 10^b hinged together at 10^c, the casing being preferably formed in this manner so that it can be conveniently folded into a compact form and easily carried from one place to another. It will be seen by referring to Figs. 1 and 5 that by swinging the part 10^b of the casing upon the part 10^a, the

casing can be opened so that the two parts will lie in the same longitudinal plane and have their inner ends abut against each other. It will be clearly understood that 60 both parts of the casing are exactly similar in construction. The top of the casing is formed with a longitudinal slot 11, and mounted to swing upon the casing are side flaps 12, which when in open position lie in the horizontal plane of the top, the top being preferably indicated by the numeral 13. Mounted within the casing are tracks 14 and at one end of the casing in one of the parts, 10^b, there is arranged a bracket 15 carrying 70 a horizontally disposed rod 16 upon which is secured a spirally wound and contractile spring 17, the rod 16 having a head 18 against which one end of the spring abuts, with the other end of the spring abutting 75 against the bracket 15, the spring being normally in its extended position.

Suitably lithographed, printed or pasted upon the top 13 on both sides of the longitudinal slots 11 are pictures 19, which in this instance represent the sea and shore, a number of ships such as water vessels, trawlers and merchant vessels being suitably shown in various positions with terms, such as, "Return to base," "Interned," or "Captured" 85 suitably imprinted or otherwise arranged upon the pictures at desirable places, suitable numbers being also employed if desirable.

In Fig. 6 I disclose a form of carriage 20 which may be in the nature of a torpedo body 21 carried on suitable uprights 22 secured to a base or running gear 23, having wheels 24 operating over the tracks 14, and side guide wheels 25 operating against the 95 inner sides of the casing. The carriage also has a plurality of oppositely extending indicators 26, and it will be seen that the carriage can very readily be arranged in the casing by placing the same within the open 100 end thereof and that the running gear will then be disposed inside the casing, whereas, the uprights 22 will project through the longitudinal slot and the torpedo body 21 lie outside the casing and immediately over the 105 pictures so that the indicators 26 will when the carriage is in a stationary position, indicate certain of the illustrations, or terms, on the top of the casing.

Now when the device is in the position 110 shown in Fig. 1 and 2, the first person playing the game hauls or pushes the torpedo

or carriage toward the right-hand end of the casing shown in Fig. 1, and then giving it a quick push causes the carriage to operate in the casing and run over the tracks 14, 5 thereby resulting in the carriage striking the head 18 of the rod 16 carrying the spring 17. This will result in contraction of the spring and as it returns to normal position, it will give an impetus to the carriage, causing the 10 same to return along the tracks and when the carriage loses the momentum it will stop, and the indicators indicate certain of the devices or terms depicted in the pictures, and acting in accordance with the rules of 15 the game this will denote the particular part in the game which the person playing first has arrived at, as will be readily understood. The next person now operates the device in a similar manner, and so the game proceeds 20 until in this instance of warfare one of the parties representing one of the warring nations, wins out over the other party.

It will be seen by referring to Fig. 3 that the side pieces 12 can be folded over the top 25 13 to close the slot 11, and it will be seen that by breaking the casing in the middle at the point where the two parts 10^a and 10^b are hinged, the torpedo or carriage can be readily removed, so that the device can be 30 packed in a small compact and portable form.

From the foregoing description it will be clear that the device can be made up in

various forms and may be used in the nature of a game determining automobile routes 35 from one city to another, or for various other purposes, and that I do not limit myself to the particular description set forth herein, nor to the particular disclosure in the drawings; the scope of the invention being indicated in the appended claims:

1. A game apparatus comprising a hollow casing closed at its ends and provided in its top with a longitudinal slot and indicia, and a carriage movable longitudinally within 45 said casing and having an indicator portion projecting through said slot, said casing being formed of hinged sections swingable one upon the other whereby said carriage may be inserted within or withdrawn from the 50 resultant open end.

2. A game apparatus comprising a hollow casing closed at its ends and provided in its top with a longitudinal slot and indicia, and a carriage movable longitudinally within 55 said casing and comprising a body, wheels upon said body bearing upon the bottom of said casing, laterally disposed wheels on said carriage bearing against the sides of said casing, uprights on said body extending through said slot, and an indicator member on said uprights cooperating with said indicia.

In testimony whereof I affix my signature.

WILLIAM T. BROOKS.
